UNITED STATES PATENT OFFICE.

GEORGE RILEY ROGERS, OF CHELSEA, IOWA.

COVER-FASTENER.

SPECIFICATION forming part of Letters Patent No. 536,896, dated April 2, 1895.

Application filed January 28, 1895. Serial No. 536,483. (No model.)

To all whom it may concern:

Be it known that I, GEORGE RILEY ROGERS, a citizen of the United States, residing at Chelsea, in the county of Tama and State of Iowa, have invented certain new and useful Improvements in Cover-Fasteners; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to certain new and useful improvements in fasteners for chests, boxes, &c., and the object of the invention is to produce a sliding hinge, which will allow the top or cover to be swung back and to rest against one side of the chest while the box is left open, and when it is desired to close the cover over the box or chest, the eyes carried by the said cover slide on a continuous wire, which wire, is formed at its free end into a spring catch providing a lock for the top, there being two of these wires, one at either end of the chest, and suitable hooks are provided, which are carried on the cover and designed to engage with the free ends of the catch rods.

To these ends and to such others as the invention may pertain, the same consists further in the novel construction, combination and adaptation of the parts as will be herein-after more fully described and then specifically defined in the accompanying drawings, in which similar letters of reference indicate like parts throughout the several views, in which—

Figure 1, is a perspective view of my fastener shown as attached to a chest and cover, parts being broken away so as to show the location of the fastener. Fig. 2, is an end view of the chest with the cover shown in dotted lines turned back against one of the sides. Fig. 3 is a detail view of the end of the chest from above; Fig. 4, an enlarged detail of the fastener.

Reference now being had to the details of the drawings by letter, A designates a chest or box of any ordinary construction, and B the top or cover for the same.

C is a bar of iron or a wire of spring metal having one of its ends securely attached to

the end of the box or chest at c. The said wire or rod is bent at right angles at D, and is bent outward slightly at the points d, and d', and is held to the end of the chest, near the top, at the points e, e, by means of the staples E. The free end F terminates in a right angled bend and extends outward, there being a recessed portion in the end of the box so as to allow the free end of the said rod to spring back therein.

The cover carries the eyes G which slide on the rods or wires C, and the hooks H, which when the cover is closed snaps over the wire at the point g securely locking the cover to the chest. The cleats H are recessed at J, in which a finger may be inserted to depress the free end of the said wire to disengage the same from the hook carried by the cover.

The operation of my invention will be readily understood, as when it is desired to remove the cover, the operator presses in from each end of the chest on the outwardly extending free ends of the said rods, and the hooks are freed from the wire, and the cover is allowed to slide back on the horizontal portion of the wire until the corner is reached, and then to be lowered down the back side 80 and in a plane parallel therewith.

Having thus described my invention, what I claim to be new, and desire to secure by Letters Patent, is—

An improved fastening for the covers of 85 chests trays &c., consisting of the wire or rod C fixedly secured to the lower end corner of a chest slightly bent outward and vertically nearly the length of the end thereof then bent at right angles and extending across the top 90 of the end portion and held thereto by suitable means, the free end of the said rod terminating at right angles to the end of the chest and being capable of being depressed into a recess, combined with a cover having 95 eyes and mounted on the said rod and carrying hooks adapted to engage with the resilient free end of the rod C, as and for the purpose set forth.

In testimony whereof I affix my signature 100 in presence of two witnesses.

GEORGE RILEY ROGERS.
